UNITED STATES PATENT OFFICE.

HERMAN E. MATHIAS, OF BROOKLYN, NEW YORK.

NURSERY RATTLE AND TOY.

1,223,507.

Specification of Letters Patent. Patented Apr. 24, 1917.

Application filed August 5, 1916. Serial No. 113,254.

To all whom it may concern:

Be it known that I, HERMAN E. MATHIAS, a citizen of the United States, and a resident of the city of New York, borough of Brooklyn, in the county of Kings and State of New York, have invented a new and Improved Nursery Rattle and Toy, of which the following is a full, clear, and exact description.

This invention relates to a nursery article 10 in the form of a combined rattle and toy.

The invention has for its object to provide a rattle which includes a toy in the form of a figure or freely movable object which moves about in the use of the rattle, and the motions contribute greatly to the amusement of 15 the infant.

A more specific object of the invention is the provision of a rattle having a suitably-shaped body to which a handle is connected, 20 and at least a portion of the wall of the body is made transparent so as to reveal a roly-poly or any other object which moves freely as the rattle is shaken or tilted, there being also in the body, pebbles, shot or equivalent 25 rattling particles which rattle when the article is shaken.

With such objects in view and others which will appear as the description proceeds, the invention comprises various novel features 30 of construction and arrangement of parts which will be set forth with particularity in the following description and claims appended hereto.

In the accompanying drawing, which 35 illustrates one embodiment of the invention and wherein similar characters of reference indicate corresponding parts in both the views,

Figure 1 is a perspective view of the combined rattle and toy; and

Fig. 2 is a vertical section.

Referring to the drawing, A designates the body of the article which is of any approved construction and suitably attached 45 to the body is a handle 1 which is preferably provided with a teething ring 2. In the present instance the body A is cylindrical, with hemispherical heads or ends, but this shape or arrangement is not essential, as the body may take a variety of forms. A portion 50 of the wall of the body is transparent so as to reveal the interior. In the present in-

stance the cylindrical part 3 is made of transparent celluloid while the hemispherical heads 4 and 5 are of opaque celluloid 55 of white or any other color. The handle 1 is connected with the head 5, and this head may be provided with a disk or partition 6 to divide the body into separate compartments 7 and 8. In the larger compartment 7 60 is arranged a roly-poly 9, or any other freely movable figure or object which moves about when the rattle is handled, and as this roly-poly is seen through the transparent wall 3, its motions add greatly to the amusement of 65 the infant. The compartment 8 contains a plurality of pebbles or other small rattling elements 10 which are concealed from view.

From the foregoing description taken in connection with the accompanying drawing, 70 the advantages of the construction and method of operation will be readily understood by those skilled in the art to which the invention appertains and while I have described the principle of operation, together with the article which I now consider to be the best embodiment thereof, I desire to have it understood that the article shown is merely illustrative, and that such changes may be made when desired as fall 80 within the scope of the appended claims.

Having thus described my invention, I claim as new and desire to secure by Letters Patent:

1. A combined rattle and toy comprising 85 a hollow body having a portion of its wall transparent, a handle connected with the body, rattle elements in the body, and a toy element also in the body.

2. A combined rattle and toy comprising 90 a hollow body having a transparent wall through which the interior of the body is seen, a figure freely mounted in the body to roll around therein, and a handle connected with the body.

3. A combined toy and rattle comprising 95 a body having a transparent wall, a partition dividing the body into two compartments, one of which includes the transparent wall, a freely movable figure in the compartment having the transparent wall, rattle elements in the other compartment, and a handle connected with the body.

4. A rattle including a hollow body hav-

ing a transparent wall, a handle connected with the body, and a roly-poly in the body.

5. A rattle including a hollow body having a transparent wall, a handle connected with the body, and a roly-poly in the body, there being a flat surface in the body on which the roly-poly is freely movable.

6. A combined rattle and toy comprising

a body, a handle connected therewith, and a figure freely movable in the body, said body comprising a cylindrical transparent section, opaque heads, and a partition in one of the heads, and rattle elements in the head having the partition. 10

HERMAN E. MATHIAS.
